DESIGN FOR A DISPLAY CABINET

John Soldani, Southbridge, Mass., assignor to Bourjois, Inc., New York, N. Y., a corporation of New York

Application August 23, 1933. Serial No. 49,098

Term of patent 14 years

To all whom it may concern:

Be it known that I, JOHN SOLDANI, a citizen of the United States of America, residing at Southbridge, county of Worcester and State of Massachusetts, have invented a new, original, and ornamental Design for a Display Cabinet, of which the following is a specification, reference being had to the accompanying drawings, forming a part thereof.

I claim:—

The ornamental design for a display cabinet as shown.

JOHN SOLDANI.
